UNITED STATES PATENT OFFICE.

GEORGE J. CARTER, OF KENTON, OHIO.

PRISON-DOOR-LOCKING MECHANISM.

No. 812,687.

Specification of Letters Patent.

Patented Feb. 13, 1906.

Application filed July 27, 1904. Serial No. 218,361.

To all whom it may concern:

Be it known that I, GEORGE J. CARTER, a citizen of the United States, residing at Kenton, Hardin county, Ohio, have invented certain new and useful Improvements in Prison-Door-Locking Mechanism, of which the following is a specification that will enable those skilled in the art to which my invention pertains to make and use the same, reference being had to the accompanying drawings, which form a part thereof.

My invention relates to locking mechanism for a series of cell-doors on a prison-corridor to be controlled and operated from a point outside of the corridor. Its principal objects are to enable an operator outside of the corridor through suitable means to so control the individual locks on the respective doors of the series that they may be dead-locked against being unlocked from the corridor by keys, or snap-locked, so that they may be unlocked from the corridor by keys, or unlocked, so that the doors may be opened without the use of keys; and my invention consists of such features and combinations of features adapted to effect its objects, as will hereinafter be fully described and claimed.

In the accompanying drawings, which show my invention in form of detail and assemblage of parts now deemed most desirable by me; Figure 1 is a front elevation of the corridor-face of a series of cells, partly in section, through the wall separating the corridor from the anteroom in which is located the lock-operating mechanism. Fig. 2 is a horizontal section of the same on the line 2 of Fig. 1. Figs. 3 and 4 illustrate different positions of the locking parts at the doors. Fig. 5 is a face view of the exterior lock-controlling mechanism.

The cells A of a series are separated from each other by wall-plates a and from the corridor B by a wall-plate a', in which are the door-openings A'. Grated sliding doors C, adapted to close the openings, are carried in front of the corridor-wall by roller-hangers D, mounted in suitable guide-tracks d, located above the door-openings and preferably inclosed in a box-casing d', suitably slotted at bottom for the passage of the roller-hangers. At one side of each door-opening is a vertical jamb-box E, having on the side nearest the door slots e for the entrance of latch-hooks c, rigidly secured upon the for-

ward edge of the door. This jamb-box extends from the floor to the under side of the box-casing d', with which it communicates, and in it is a movable lock-bar F, having apertures f, adapted to engage the latch-hooks when the door is closed.

Owing to the narrowness of the jamb-box, the latch-hooks project across and beyond it, but they are guarded against access by cast-metal caps e', secured upon the farther side of the box. On the jamb-box is secured a key-lock O, having a rotatable barrel o, to which is attached a gear-segment o', which engages a series of gear-teeth o'' on the face of the lock-bar F. By means of this device the lock-bar may be operated by the key-lock under certain conditions, as will hereinafter be explained. A dead-lock P may also be used on the door to lock it independently of the other locking mechanism and hold it locked while the mechanism is operating on the other doors of the series. The latch p of this dead-lock engages a slot in the wall of the jamb-box, and it lies in a slot p' in the lock-bar F of such length that the movement of the lock-bar does not affect this catch or release it from its hooked engagement with the wall of the jamb-box.

The upper end f' of the lock-bar projects out of the jamb-box and is preferably twisted, as shown, and provided at its extremity with a cross-pin f''. This cross-pin is engaged by one arm of a bell-crank lever G, pivoted on a stud-pin g on the front cell-plate a'. The cross-pin lies in a slot g' in the bell-crank, which under certain conditions allows of independent movement of the lock-bar F. The other or depending arm g'' of the bell-crank is connected by a cross-pin h to a master-bar H, which extends above all of the doors in the series, and through a wall-plate I, which separates the corridor from the exterior or anteroom I'. The bell-cranks G of all the doors are similarly connected to the master-bar, so that they are moved uniformly and in unison by it. The end of the master-bar projecting into the anteroom is connected to mechanism K, located in said room and outside of the corridor, adapted to move the master-bar longitudinally and preferably provided with an indicator to register the movement. The preferred form of this mechanism is illustrated in the drawings, and it consists of a lever J, pivoted at j and connected

at its upper end by a pin-joint h' to the master-bar. The lower end of the lever is provided with a gear-segment J' , which vibrates in a guide j' and is engaged by a worm k , 5 mounted on a shaft K' , supported in a bracket k^2 . The projecting end k^3 of the shaft is squared to be engaged by a removable socket-crank k^4 . A fixed graduated scale or indicator L and a pointer l , attached to the lever, 10 indicate the degree of movement of the master-bar and bell-cranks. All of this mechanism is preferably inclosed in a secure casing M , having a door m , provided with handle m' and lock m^2 , as shown.

15 In the operation of my invention the locking mechanism of all the doors may be operated by the actuating mechanism K through the master-bar and the vertically-slotted bell-cranks, either to dead-lock all the lock-bars 20 F , as shown in Fig. 1, or to snap-lock them, as shown in Fig. 3, or to lift and unlock them, as shown in Fig. 4. In the position of the bell-crank shown in Fig. 1 its slot end bears down upon the stud-pin g and dead-locks the lock-bar against being raised and unlocked by any 25 means. On the mid-position of the bell-crank shown in Fig. 3 its slot is up on the pin, leaving the lock-bar free to be raised and unlocked by the key-lock O . In the extreme position of the bell-crank shown in Fig. 4 the lower end of the slot has contacted with the pin before the termination of the movement of the bell-crank, so that its further movement has carried the lock-bar up 30 with it and unlocked the door. With the mechanism outside of the corridor the operator is therefore enabled to set all the locks "dead" against being unlocked or to set them "snap," so that they may be opened individually by keys, or to unlock all of them, except such as may be held by the dead-locks P .

35 Having thus described my invention, what

I claim as new and useful, and desire to secure by Letters Patent, is—

1. The combination of a cell-door having 45 locking mechanism, a vertical bar adapted to engage with said locking mechanism, a cross-pin on said bar with a bell-crank lever having one arm vertically slotted to engage said cross-pin and a master-bar for a series of 50 doors connected to the other arm of the lever, substantially as described.

2. The combination of a cell-door having rigid latch-hooks, a jamb-box apertured for the reception of said hooks, a vertically-movable lock-bar located in said jamb-box and having apertures adapted to engage the latch-hooks the upper end of the bar extending out of the jamb-box, a cross-pin on the upper end of the bar and a bell-crank lever having one 60 arm vertically slotted to engage said cross-pin, a master-bar connected to the other arm of the bell-crank, with a key-lock on the jamb-box having a rotatable barrel with a toothed segment and a rack on the lock-bar engaged 65 by said segment, substantially as described.

3. The combination of a cell-door having rigid latch-hooks, a jamb-box apertured for the reception of said hooks, a vertically-movable bar in the jamb-box apertured to engage 70 said hooks, a dead-lock on the door having a hooked latch adapted to engage an aperture in the jamb-box and a slot in the lock-bar of such length that the movement of the bar will not actuate the hooked latch of the dead-lock, substantially as described. 75

In testimony whereof I have signed my name to this specification in the presence of two subscribing witnesses.

GEORGE J. CARTER.
